UNITED STATES PATENT OFFICE.

ARTHUR C. MCWILLIAMS, OF CHICAGO, ILLINOIS.

COMBINED MOTOR-STARTER AND CIRCUIT-BREAKER.

1,092,281.

Specification of Letters Patent.

Patented Apr. 7, 1914.

Application filed June 19, 1912. Serial No. 704,521.

To all whom it may concern:

Be it known that I, ARTHUR C. MCWILLIAMS, a citizen of the United States, residing at Chicago, in the county of Cook and State of Illinois, have invented a certain new and useful Improvement in Combined Motor-Starters and Circuit-Breakers, of which the following is a specification.

My invention relates to motor starters and constitutes more specifically a combined motor starter and circuit breaker for direct current motors.

It is well known that according to common practice when a direct current motor is to be started, the first step in the operation is to see that the rheostat or controller is in position where the entire resistance will be in series. The operator then closes the main circuit switch which connects the rheostat and motor with the mains, after which he manipulates the rheostat in such manner as to gradually cut out the resistance as the motor increases its speed up to normal. This method involves two distinct operations which must be done in proper sequence, and furthermore, requires the operator to wait at the rheostat until the motor has attained its full speed and it is safe to cut out the artificial resistance. This not only incurs a loss of time, but if the operator is in a hurry he is apt to cut out the resistance too rapidly and thereby run the risk of burning out the motor.

The object of my invention is to provide apparatus by which the whole process may be automatically accomplished by the mere throwing of a handle. By using my apparatus, it is merely necessary for the operator to throw an operating handle or lever from one position to another, whereupon all of the above mentioned steps in the starting of the motor will take place in proper sequence, and with the proper amount of time devoted to each step.

I accomplish my object by the mechanism illustrated in the accompanying drawings, in which—

Figure 1 is an elevation chiefly in central section of the complete apparatus. Fig. 2 is a vertical sectional view on the line 2—2, Fig. 1. Fig. 3 is a plan section on the line 3—3, Fig. 1. Fig. 4 is a detail of the operating handle, and Fig. 5 is a diagram showing the wiring.

The apparatus is inclosed within a casing comprising preferably a base 1, forming a

receptacle adapted to contain oil or other fluid non conductor. This is covered by a plate 2 which supports certain parts of the apparatus. Above platform 2 is a housing 3. Journaled within the housing is a shaft 4 which, at one end, projects through the housing and carries on the projecting end an operating handle or lever 5. The hub of this handle is loosely mounted upon shaft 4 so as to be rotatable independently thereof. A collar 6 is rigidly fastened to the shaft adjacent to the hub of the handle, and this is provided with two notches 7 and 8, best shown in Fig. 4. These notches are 180 degrees apart in the present design and are adapted to receive the nose of a dog 10 which is mounted so as to slide longitudinally upon handle 5. In the preferred design, said dog is guided by lugs 11 on the handle. A rod 12 is fastened at one end to the dog and at the other end is connected to a hand grip 13 which is pivotally mounted upon a pin 14 carried at the free extremity of the handle. A coiled spring 15 encircles rod 12, and at one end abuts against the lug 16 rigidly mounted upon said handle. At the other end said spring contacts a block 17 rigidly fastened to the rod, and the parts are so arranged that the spring normally tends to hold the dog out of the notches. By gripping the free end of the handle, however, the operator will so press the hand grip as to force the dog toward collar 6 and into one or the other of said notches. Obviously, therefore, the handle is normally free, but the act of the operator in grasping the handle will cause it to engage the collar so that the collar and shaft will be rotated when the handle is rotated.

A pinion 20 is mounted on shaft 4 in position to mesh with a rack 21 which is arranged vertically, and is fastened at its lower end to a vertical tube 23. A platform 24 is fastened to the lower end of said tube and supports a number of coiled compression springs 25. These springs are preferably four in number and encircle rods 26 which are rigidly fastened at their upper end to the platform 2 and are rigidly fastened at the lower end to the upper head 27 of the cylinder 28. Thus the rods 26 are stationary and serve as guides for certain parts of the apparatus, among them the platform 24 which is apertured to receive 110 and slide along said rod.

Resting upon the top of springs 25 is an

insulating block 29, to which are fastened bars 30 which form switch blades adapted to enter the switch jaws 31, 32 for connecting the main supply conductors 33 with the rheostatic resistances hereinafter described. Said switch jaws in the present design are fastened to insulating blocks 34, fastened to the underside of platform 2.

The insulating block 29, above mentioned, 10 is centrally apertured so it can slide freely in a vertical direction relatively to the vertically movable tube 23. Interposed between the top of block 29 and the underside of platform 2 are coiled compression springs 15 38 which are preferably four in number and encircle the upper end of the stationary rods 27. These springs 38 are stronger than the springs 25.

A vertical rod 40 is fastened at the lower 20 end to a plunger 41 which fits within the cylinder 28 and has apertures 42 for permitting the oil with which the apparatus is filled to pass upward through the plunger and permit the latter to descend at a comparatively rapid rate of speed. A disk 43 rests upon plunger 41 and is apertured to freely slide vertically upon rod 40. The upward movement of said disk is limited by a collar 44 formed upon said rod. When the 30 disk is upon the plunger it prevents the oil from passing downwardly through the plunger. The cylinder head 27 has apertures 46 for permitting the oil to escape through the top of the cylinder. The cylinder, plunger 35 and valve disk just mentioned, form a dash pot for retarding the upward travel of rod 40 and parts connected thereto. The rate of upward movement of rod 40 and connected parts is controlled by a valve 47 which 40 controls a port 48 at the lower end of cylinder 28, as best shown in Fig. 1. Rod 40 projects up through the cylinder head 27 through the plate 50 hereinafter again referred to, through the platform 24 and up 45 into the tube 23. At the upper end it has a head 51 rigidly fastened thereto. Interposed between the head 51 of the rod and the platform 24 is a coiled compression spring 52 which encircles rod 40 and tends to raise 50 it as fast as the dash pot will let it when the platform 24 is raised at the time the device is first set into operating condition.

The plate 50 is pinned or otherwise rigidly fastened to rod 40 and carries at its ends 55 pending arms 56 which carry contactors at their lower ends, as best shown in Fig. 1, and diagrammatically at the lower end of Fig. 5. In the preferred design here shown, the contactors each consist of a connector 60 bar 57 carrying outwardly pressed blocks 58 of conducting material, adapted to engage the rheostatic contacts 59. These contacts 59 are electrically connected in series through resistances 60, the lowest contacts 65 being preferably electrically connected with

each other through a conductor 61. In the best design, these rheostatic resistances are arranged in two banks, as shown in Figs. 1 and 5, which makes it possible to arrange the apparatus more compactly, reduce the necessary amount of travel and by reason of the symmetry with respect to its central axis, balance the mechanical strains and thus enable the apparatus to operate more smoothly, with less liability of getting out of order. 70 The two banks of the said resistances are connected at the end by the conductors 65, 66, and 67 to one of the jaws 32. The remaining two banks of the said resistances are connected by the conductors 70, 71, and 72 to one terminal of the armature of the motor which is to be controlled. The arrangement is such that when the plate 50 is down in its lowest position, as shown in Figs. 1 and 5, the entire resistance of the 85 apparatus will be in series with the motor armature. As plate 50 rises, the resistance will be gradually cut out. Thus the resistances and the plate 50 and attached parts constitute a rheostat or controller, and the 90 plate 50 and attached parts constitute the movable element of the controller. The movable element of the controller may be properly termed also a "rheostatic switch."

In Fig. 1 the parts are shown in normal 95 position prior to starting. The rheostatic contactors 58 are at their lowest position with the entire resistance in series, the plunger 41 of the dash pot at its lowest position, and the switch blades 30 down out of contact 100 with the jaws 31, 32. The tube 23 and rack 21 are also at their lowest position. Taking the parts in this normal non acting position, a collar 75 is rigidly fastened on the outside of tube 23 at some distance below block 105 29. Said collar is adapted to engage said block after the tube has risen part way, and the function of the collar is to raise said block and the switch blades or bars 30 into engagement with the jaws 31, 32. The parts 110 are so proportioned that when the rack, tube, and platform 24 rise, they will travel a considerable distance and compress the springs 25 and 52 without raising the switch blades into engagement with said jaws, the 115 springs 38 being strong enough to prevent such engagement. Finally, however, the collar 75 will engage block 29, and the final portion of the upward movement of tube 23 and collar 75 will force blades 30 home into engagement with the jaws 31, 32, thus closing the circuit to the main feed conductors. A collar 76 is fastened to tube 23 above block 29, its function being to engage said block when the tube and rack are nearing 125 their lowest position, and positively force the blades out of engagement with the jaws, thus insuring, as the last step, the breaking of the circuit of the apparatus with the main feed conductors. 130

I have now described the manner in which the rack 21 may be elevated through the medium of the handle 25. I will next describe the mechanism for holding the rack 5 and its connected parts at their uppermost position after they have been moved there by the handle. In general, this holding mechanism consists of a detent for preventing rotation of the shaft 4 in what may be 10 termed the "return" direction; that is the direction which permits the rack to descend and lower the parts to normal position. In the form of apparatus shown in the accompanying drawings, the said detent is first 15 set by gravity and thereafter held electromagnetically. Referring to this holding mechanism, which is shown more particularly in Fig. 2 and the upper portion of Fig. 1, a detent lever 80 is pivoted upon a 20 stationary pin 81. Said pin may be carried by any convenient stationary portion of the apparatus, in the present design being mounted upon the bracket 82 rigidly fastened to the frame 84 of the electromagnet 83 fastened upon the platform 2. 25 In the preferred design here shown, said lever is L shaped and so arranged that one portion extends horizontally, while the other portion extends vertically from fulcrum pin 30 81. Upon the horizontal portion of lever 80 is a pin 85 provided preferably with an anti-friction roller. Said pin is adapted to engage the shoulder 86 formed upon the snail cam 87 rigidly secured to shaft 4. It 35 is obvious that the weight of the rack 22 and connected parts, and the influence of the springs 25, 38 and 52 tend to lower said rack and associated parts and rotate pinion 20 in the return or clock-wise direction, Fig. 40 2. The parts just mentioned are so arranged that when the rack 21 is at its uppermost position, pin 85 will drop down behind shoulder 86 and hold the shaft and pinion 45 locked against "return" rotation. By raising the horizontal arm of lever 80 the cam will be released and the rack permitted to descend. According to the present design, there are, as above stated, two things which 50 tend to hold pin 85 in engagement with shoulder 86, to-wit, gravity and magnetism. Gravity is availed of through the medium of a weight 90 placed on the end of lever 80 outside of the case cover 3. Said lever projects through a slot 91 formed in the side 55 of the cover, as shown in Fig. 2, and the projecting end of the lever forms a handle which the attendant may grasp for the purpose of lifting pin 85 out of engagement with the cam shoulder 86 to release the 60 mechanism when it is desired to shut down the motor. The electromagnetic means for holding the detent lever 80 in set or acting position comprises the electromagnet 83, above mentioned, the frame whereof when 65 energized is adapted to act upon the ver-

tical arm of lever 80 and urge it toward the center of shaft 4, thus insuring secure engagement with shoulder 86.

I have provided an overload device for automatically releasing the detent lever 80 from engagement with shoulder 86 in case excess of current should be supplied to the motor. An electromagnet 95 is provided with a centrally arranged stationary tube 96, in which a core 97 is slidably mounted. Said core normally rests upon a stop-screw 98 mounted in the head 99 at the lower end of said tube. The hammer 100 is slidably mounted at the upper end of tube 96 in position to strike the lower edge of the horizontal arm of lever 80 and elevate the same. The parts are so designed that when the coil 95 is energized the core 97 will rise and strike hammer 100, which in turn strikes the lever 80 a hammer blow and forcibly raises pin 85 out of engagement with the shoulder 86.

In operation, let it be assumed that the motor is still and that the parts occupy the normal position shown in Fig. 1. If, now, 90 the operator wishes to start up, he grasps the handle 5 at the hand grip 13, thus forcing dog 10 into one of the notches in the collar 6. He then rotates the handle approximately 180 degrees, which rotates 95 shaft 4 to such an extent that the rack 21 will be raised to its uppermost position and pin 85 will engage the cam shoulder 86 and retain the parts set in this position. The upward movement of the rack 21 and of the 100 tube 23 secured thereto causes the platform 24 to compress the springs 25 until the collar 75 engages the block 29. The remaining portion of the upward movement of the tube 23 and collar 75 causes the latter to 105 force the blades 30 into engagement with the jaws 31, 32 and thus closes the circuit to the feed wires. The block 29 and blades 30 will not move upwardly to any great extent until after the collar has engaged the 110 block, because the springs 38 are considerably stronger than the springs 25 and will not yield much until the collar has actually engaged the block. The upward movement of tube 23 and platform 24 also causes the 115 compression of spring 52, for the rod 40 cannot be moved rapidly, owing to the retarding effect of the plunger 41 in the dash pot cylinder 28; consequently the circuit will be closed through the main switch 120 blades 30 before the rod 40 and attached plate 50 will have moved any appreciable distance. The compressive strain of spring 52, however, will slowly force the rod 40 and plate 50 and the attached rheostat connectors upward and gradually cut out the resistances 60 which are in series with the motor armature. This will be clearly understood by referring to the diagram of Fig. 5, in which the motor 125 5 is shown to 130

have its armature 106 in series with said resistances when the circuit through the feed wires is closed. After due time has elapsed, spring 52 will have raised the connectors 58 to their topmost position at which point all of the rheostatic resistance will be cut out of circuit and the motor will be running at full speed.

In the diagram, Fig. 5, will be seen that 10 the overload coil 95 is in series with the motor armature, consequently if the current supply to the motor becomes too great it will be energized sufficiently to trip the lever 80 and release the shaft and rack. The diagram also shows that the holding coil 83 encircling the magnet frame 84 is in series 15 with the motor field coils 108, and that these are energized as soon as the switch blades 30 are moved to closed position.

Having thus described my invention, what 20 I claim as new and desire to secure by Letters Patent, is:

1. A combined motor starter and circuit breaker comprising a main switch, a movable motive element adapted to engage said switch for closing it, there being lost motion of said movable element from normal non-acting position before said movable element engages said switch, a rheostatic controller 25 in circuit with said switch and having a movable element adapted to vary the amount of resistance in circuit, means actuated by said motive element for urging the movable element of the controller in a direction to 30 cut out resistance, means for automatically controlling the rate of movement of the movable element of the controller when moving in a direction to cut out resistance, and a spring actuated by said motive element 35 for urging said movable controller element in a direction to cut in resistance.

2. A combined motor starter and circuit breaker comprising a main switch, a movable motive element adapted to engage said switch for closing it, there being lost motion 45 of said motive element from normal non-acting position before said motive element engages said switch, a rheostatic controller in circuit with said switch and having a 50 movable member adapted to vary the amount of resistance in circuit, a spring actuated by said motive element for urging the movable member of the controller in a direction to cut out resistance, means for 55 retarding the action of said spring and a spring actuated by said motive element for urging the movable member of the controller in a direction to cut in resistance.

3. A combined motor starter and circuit 60 breaker comprising a main switch, a movable motive element adapted to engage said switch for closing it, there being lost motion of said movable element from normal non-acting position before said movable element

engages said switch, a set of resistances in 65 series with said main switch, a movable controller member adapted to vary the amount of said resistance in circuit, a spring actuated by said motive element for urging said controller member in a direction to cut out 70 resistance, a dash pot for retarding the movement of said controller member and a spring actuated by said motive element for urging said controller member in a direction to 75 cut in resistance.

4. In a motor starter, the combination of a main switch for connecting and disconnecting the source of supply with the motor to be controlled, resistances arranged in four parallel banks, the end of two banks being 80 connected to the armature of the motor and an end of the remaining two banks being connected to one of the terminals of said main switch, a controller having two connectors, each connector being adapted to engage two of said banks of resistances simultaneously, the motion of said controller in one direction causing resistance to be cut out of circuit and the motion in the opposite direction causing resistance to be cut into 85 circuit, a movable element adapted to operate said main switch, a spring actuated by said movable element and adapted to move said controller in a direction to cut out resistance, and means for retarding the movement of said controller.

5. In combination, a switch having a movable blade, a relatively strong spring acting upon said blade to hold it in open position, a relatively weak spring acting upon said movable blade to urge it to closed position, a movable element acting upon said weak spring to increase its action upon said switch blade, and engaging means upon said movable element adapted to engage said switch blade and force it to closed position against the action of the stronger spring, said engaging means lying at a distance from the switch blade when the parts are in normal position, whereby the engaging means is permitted to move a certain distance before engaging said switch blade, substantially as described.

6. A combined motor starter and circuit breaker comprising a main switch for the 115 motor, rheostatic resistance in circuit relation with the main switch and motor, a rheostatic switch for cutting the rheostatic resistance into and out of circuit with the motor, a motive element, a spring interposed between said motive element and said main switch for closing the main switch when the motive element is moved in forward direction, means operated by said motive element for opening said main switch, 120 and a second spring interposed between said motive element and said rheostatic switch for moving the rheostatic switch in a direc- 125

tion to cut out resistance when said motive element is moved in a direction to close the main switch, the first mentioned spring tending to move said rheostatic switch in a direction to cut out resistance when said main switch is in open position.

7. A combined motor starter and circuit breaker comprising a main switch for the motor, rheostatic resistance in circuit relation with the main switch and motor, a rheostatic switch for cutting the rheostatic resistance into and out of circuit with the motor, a motive element, opposing springs acting at their adjacent ends upon said main switch, the far end of one of said springs being held stationary and the far end of the second of said springs being acted upon by the motive element, said motive element being operative upon said rheostatic switch to force it in a direction to cut in resistance, and a third spring interposed between said motive element and said rheostatic switch for moving said rheostatic switch in a direction to cut out resistance.

25 8. A combined motor starter and circuit breaker comprising a main switch for the motor, rheostatic resistance in circuit relation with the main switch and motor, a rheostatic switch for cutting the rheostatic resistance into and out of circuit with the motor, a motive element, a spring interposed between said motive element and said main switch for closing the main switch when the motive element is moved in forward direction, means operated by said motive element for opening said main switch, a second spring interposed between said motive element and said rheostatic switch for moving the rheostatic switch in a direction to cut out resistance when said motive element is moved in a direction to close the main switch, the first mentioned spring tending to move said rheostatic switch in a direction to cut out resistance when said main switch is in open position, and means for retarding the action of said second spring.

9. In a device of the class described, the combination of a main switch, starting resistance, a controller adapted to coöperate with said starting resistance to cut it in and out of circuit, a spring for operating said controller, a movable element adapted to operate said spring, and engaging means on said movable element above and below the switch for opening and closing it, said engaging means being located at a sufficient distance apart to permit said movable element to travel a certain distance without affecting the switch.

10. In a device of the class described, the combination of a main switch, starting resistance, a controller adapted to coöperate with said starting resistance to cut it in and

and out of circuit, yielding means for operating said controller in both directions, a movable element adapted to operate said yielding means and also to operate the main switch, and means for retarding the movement of the controller.

11. In a device of the class described, the combination of a main switch, starting resistance, a controller adapted to coöperate with said starting resistance to cut it in and out of circuit, a spring, a movable element adapted to operate said controller through the medium of said spring, means for regulating the speed of the controller under the action of the spring, and a tappet upon said movable element adapted to engage said main switch to close it, said tappet being normally at a distance from said switch whereby lost motion occurs in the movable element before the tappet acts upon the switch.

12. In a device of the class described, the combination of a main switch, starting resistance, a controller adapted to coöperate with said starting resistance to cut it in and out of circuit, a spring for operating said controller, actuating means adapted to actuate both the spring and the main switch, a hand releasable gravity actuated detent for holding said actuating means in set position, and electromagnetic means in circuit relation with the main switch for assisting gravity to hold the detent in acting position.

13. In a device of the class described, the combination of a main switch, starting resistance, a controller adapted to coöperate with said starting resistance to cut it in and out of circuit, a spring for operating said controller, a movable element adapted to operate said spring and also to operate the main switch, a detent for holding said actuating means in set position, and electromagnetic means in series with said switch for tripping said detent when the current becomes excessive.

14. In a device of the class described, the combination of a main switch, starting resistance, a controller adapted to coöperate with said starting resistance to cut it in and out of circuit, a spring for operating said controller, a movable element adapted to operate said spring and also to operate the main switch, a detent for holding said actuating means in set position, a coil in series with said main switch, and a movable core in said coil adapted to impart a hammer blow to said detent for tripping it when the current through the coil becomes excessive.

15. In a device of the class described, the combination of a main switch, starting resistance, a controller adapted to coöperate with said starting resistance to cut it in and out of circuit, a spring for operating said

- controller, a movable element adapted to operate said spring and also to operate the main switch, a detent for holding said actuating means in set position, a coil in series 5 with said main switch, a hammer adapted to trip said detent, and a movable core in said coil adapted to operate said hammer when the coil becomes sufficiently energized, substantially as described.
- 10 16. In a device of the class described, the combination of a main switch, starting resistance, a controller adapted to coöperate with said starting resistance to cut it in and out of circuit, a spring for operating said controller, actuating means adapted to actuate both the spring and the main switch, said actuating means including a rack, pinion and a rotatable shaft, a handle loosely mounted upon said shaft, a manually controlled dog upon said handle, a notched collar rigidly fastened to said shaft in position to permit the dog to enter the notch therein, and means for holding said shaft in set position after it has been rotated by 15 said handle, dog and collar.
17. In a device of the class described, the combination of a main switch, starting resistance, a controller adapted to coöperate with said starting resistance to cut it in and 20 out of circuit, a spring for operating said controller, means for retarding the movement of said controller under the action of said spring, a movable tube inclosing said spring and acting thereon to urge the controller in a direction to cut out resistance, and a tappet upon said tube adapted to engage the main switch for closing it, said tappet being normally at a distance from 25
- 30
- 35
- said switch, whereby the tube is permitted to move some distance before the tappet engages the switch. 40
18. In a device of the class described, the combination of a main switch, starting resistance, a controller adapted to coöperate with said starting resistance to cut it in and out of circuit, a spring for operating said controller, means for retarding the movement of said controller under the action of said spring, a movable tube inclosing said spring and acting thereon to urge the controller in a direction to cut out resistance, and a tappet upon said tube adapted to engage the main switch for opening it. 45
19. In a device of the class described, the combination of a main switch, starting resistance, a controller adapted to coöperate with said starting resistance to cut it in and out of circuit, a spring for operating said controller, means for retarding the movement of said controller under the action of 50 said spring, a movable tube inclosing said spring and acting thereon to urge the controller in a direction to cut out resistance, and two tappets upon said tube, one above and the other below said switch for operating it, said tappets being located at some 55 distance apart, whereby a certain amount of motion of the tube is permitted without moving the main switch. 60
